UNITED STATES PATENT OFFICE.

WILLIAM DIEFENBARGH, OF MONTPELIER, INDIANA, ASSIGNOR OF ONE-HALF TO
FRANK HEDGES, OF MONTPELIER, INDIANA.

LOCKING DEVICE FOR MOTOR-CARS.

1,384,026.

Specification of Letters Patent.

Patented July 5, 1921.

Application filed February 19, 1920. Serial No. 359,991.

To all whom it may concern:

Be it known that I, WILLIAM DIEFENBARGH, a citizen of the United States, residing at Montpelier, in the county of Blackford and State of Indiana, have invented certain new and useful Improvements in Locking Devices for Motor-Cars, of which the following is a specification.

The present invention relates to improvements in locking means for internal combustion engines, having reference especially to means of the kind described for the effectual locking of the fuel supply and ignition system of the gasoline motors of automobiles.

The purpose in this invention is to provide a device for attaching to motor cars by which the starting of the motor by unauthorized persons may be prevented, but which may be easily accomplished by the owner or any person authorized.

The invention contemplates the arrangement of a switch capable of being set at position to break the electric circuit, a valve capable of being set at position to shut off the fuel supply, a holding means to engage and hold the switch and the valve at the set positions, a casement to inclose the said holding means, switch and valve parts, and a closure plate for the casement and lock therefor.

The objects of my invention are accomplished by, and the preferred form of embodiment of my invention is shown in the new construction combination and arrangement of parts illustrated in the accompanying drawings and described in the following specification. The invention is defined in the appended claims.

The several parts of my invention are identified by suitable characters of reference applied thereto in the different views in the drawings, in which—

Figure 1 is a frontal view of my improved locking device in its standardized form as the same appears disposed at position on the dash board of any standard gasoline motor car.

Fig. 2 is a side view, as seen in the direction indicated by the arrow 2 in Fig. 1.

Fig. 3 is an enlarged view of the casement, the door thereof being at open position, to show the relative positions of the several operative parts.

Fig. 4 is a sectional top plan view taken on the line 4—4 in Fig. 3.

The casement 1 in which the operative parts of my invention are inclosed may be made of aluminum and may be secured to the dash board A by screws or bolts passed through the holes 2. Extending from an opening in the lower side of the casement, is a tubular casing 3 of suitable length at whose bottom is arranged a housing 4. Retained in this housing is a gate type valve 5 provided with standard union joint connections 6 and by which it may readily be connected into the fuel gasoline line pipe B common to all motor cars. Extending upwardly from the valve gate 5^a of the said valve is a stem 7 that is passed vertically through the casement and which has bearing in an opening provided therefor in the top side of said casement. Secured on the top of said valve stem is the valve stem head 8. Disposed in the opposite side of the casement and in alignment with the valve stem, is a member designated as a switch bar 9 and which is provided with the switch-bar-head 10. This switch bar is journaled in suitable fiber bearings 11 and 12 suitably secured to the casement. Mounted on the fiber plate 13 that is secured to the casing is a terminal plate 14 that is provided with terminals from which extend the insulated electric wires C and D forming part of the electric circuit of the ignition system common to all gasoline motor cars. Adapted to establish contact with the studs 14^a of the terminal plate 14 when the switch bar 9 is moved is the arm 9^a that is secured to the said bar 9. Secured to the switch bar 9 is a wheel 15 provided with a recess 15^a. Secured to the valve stem 7 is a wheel 16 provided with a recess having the heads 16^a and 16^b. The holding means whose function is to hold the wheels 15 and 16 against movement and which engages the recesses of these wheels in the manner as shown in Fig. 4 when the switch bar and valve stem are at position with the electric circuit open and the fuel supply shut off, consists of a pair of flat metal bars 17 each being hinged or pivoted at its lower portion on a suitable stud 18. A spring 19 having its ends connected to the ends of these bars urges them to the expanded position shown in Fig. 3, their upper ends being slidingly retained in a suitably slotted guide bar 20 connected to the casement. A central stud 21 serves to limit the travel of these bars when they are drawn together and free from

engagement with the wheels 15 and 16. To retract these bars 17 the user applies his thumb and finger to the studs 17^a and by drawing same together the bars are moved 5 to position disengaged from the wheels 15 and 16. While holding the bars at this retracted position, the switch bar head 10 is turned in the direction indicated by the arrow in Fig. 4, the arm 9^a being moved into 10 contact with the terminal studs 14^a and the circuit thus being closed. In a similar manner, the valve stem head 8 is moved in the direction indicated by the arrow and the valve in the fuel supply pipe line B is 15 opened. The distance through which the valve stem head 8 is moved, is limited by the recess head 16^b which meets the arm 22 disposed in the position shown. The switch and valve having thus been set so that the 20 circuit is closed and the fuel supply line is open, the hinged door 1^a of the casement, and upon which said door is carried a combination lock mechanism 24, is swung to, and the lock bolt 25 in its engagement with the 25 lock bar 26 secures the door at the closed position as shown in Fig. 1. By the use of a combination lock device which forms a part of the door lock mechanism, the matter of opening the door is one easy to control by 30 the car owner exclusively, or by those only to be intrusted with the combination by which the lock may be operated and the door opened. To operate the switch bar head and valve stem head to open the electric 35 circuit and to shut off the fuel supply, these heads are simply moved rotatively in the directions opposite to those indicated by the arrows; when at the positions as shown in Fig. 4, the holding bars 17 automatically 40 expand to the positions shown in such engagement with the recesses of the wheels 15 and 16 that the latter are held against being shifted, until the door 1^a will again have been opened.

45 Although the switch bar head 10 and the valve stem head 8 are disposed outside the casing and are easy of access, neither of these heads are operable until the holder bars 17 will have been retracted. Normally 50 the switch and valve occupy the positions, retained against movement, in which said

position the electric circuit is broken or open, and the fuel supply in the line B is cut off. By working the combination lock the door may be opened and access is thus 55 had to the holding means, which, when manipulated by the user, permits of the turning of the switch bar head and the valve stem head, as above described.

What I claim as my invention, and desire 60 to secure by Letters Patent, is—

1. A locking device for motor cars, comprising an electric switch capable of being set at position to open the circuit, a valve in the fuel supply line, a valve mechanism capable of being set at position to maintain the valve closed, a holding means to engage and hold the switch and the valve mechanism at the set positions, a casement to inclose the said holding means, and a lock for 70 the door.

2. A locking device for motor cars, comprising a casement, an electric switch inside but operable from outside the casement and capable of being set at position to break the 75 circuit, a valve for the fuel supply line and which is capable of being set at position to shut off the fuel supply, a valve actuating means operable from outside the casement, a holding means inside the casement to engage 80 and hold the switch and the valve mechanism at the set positions but which holding means is operable to release its hold and to permit of the movement of the said switch and valve mechanism, and a door for the 85 casement.

3. The combination of an electric switch capable of being set to maintain the circuit open, a valve for the fuel supply, a valve mechanism capable of being set at position 90 to maintain the valve closed, a holding means common to the switch and the valve mechanism to hold the said switch and the valve mechanism against being moved, but which holding means may be operated to release its hold, a casement to inclose said holding means and switch and valve actuating mechanisms, and a closure device for the 95 casement.

In testimony whereof I affix my signature. 100

WILLIAM DIEFENBARGH.
